Primary Examiner — Kevin Rudzinski(74) *Attorney, Agent, or Firm* — Stewart & Irwin, P.C.;
Dennis S. Schell; Bassam S. Nader(57) **CLAIM**

The ornamental design for a LED area light fixture, substantially as shown and described.

DESCRIPTION

FIG. 1 is a front perspective view of an LED area light fixture showing the new design;

FIG. 2 is a rear perspective view thereof;

FIG. 3 is a front view thereof;

FIG. 4 is a rear view thereof;

FIG. 5 is a top view thereof;

FIG. 6 is a bottom view thereof; and,

FIG. 7 is a left side view thereof.

The design consists of the features of shape, ornament and configuration of the article shown in the drawings. The broken lines shown in the drawings are for the purposes of illustrating portions of the article that form no part of the claimed design. The right side view is a mirror image of the left side view and is therefore omitted.
